FIRE OR DRAFT STOP FOR PIERS,
WHARVES, AND THE LIKE

John McKay, New Orleans, La., assignor to Cement Gun Company, Allentown, Pa., a corporation of Delaware

Application February 25, 1935, Serial No. 8,043

4 Claims. (Cl. 61—48)

This invention relates to fire or draft stops for piers, wharves and the like and more particularly to fire or draft stops of suitable material, such as "Gunite".

5 Piers, wharves and like structures commonly comprise suitable deck or floor structures supported by wooden piles and, in the event of fire beneath the floor of one of these structures, the fire is not only very hard to get at but tends to 10 spread very rapidly and burn out the piles, thus tending to cause collapse of the structure as a whole. It is very important therefore to obstruct or prevent the spreading of the fire beneath the floor. Heretofore this has been done by the use 15 of fire or draft stops usually made of wood or of metal plates. Such stops tend to shut off drafts but the wooden stops are very quickly destroyed when reached by the fire and the stops of metal plates or sheets, while not inflammable, are 20 quickly heated so as to set fire to supporting structures of wood and thereby cause their own collapse.

An important object of the present invention is to provide a novel and advantageous 25 device of the general character described. According to a preferred embodiment of the invention, each fire stop comprises a relatively light wall or partition of reinforced "Gunite" 30 preferably adjacent to and at least partially supported by a row of piles extending transversely with respect to the length of the pier or wharf and extending up to the floor proper and downwardly as far as feasible, for example, substantially to low water mark. The supporting piles 35 may also be surrounded by metal reinforcing means which is tied up with the reinforcement of the fire stop proper, and the piles thus prepared may be enclosed in a covering of "Gunite" integral with that of the fire stop proper, thus 40 forming a monolithic structure of which the fire resistant panels or parts between the piles are strong and flexible, so as not to be cracked or broken easily, and the piles with their casings of "Gunite" are practically fireproof.

45 Although the fire-stop structure thus far described is very effective, there is danger of fire jumping around a free end of such a fire stop. Such jumping of the fire must be guarded against and this may be done by providing at each free 50 end of the stop proper a curtain or wall of reinforced "Gunite" located along the side of the structure and arranged at either one or both ends of the fire stop. Preferably the wings formed by these curtains or walls are each in the form 55 of a panel adjacent to the inner sides of the

piles at the end of the stop proper and the next pile along the side of the pier or wharf.

In forming the panels between the piles and the casings for the piles, the metal reinforcing means, preferably in the form of a wire mesh, 5 is placed where the panels are to be made and the piles are enclosed in wire mesh secured to the wire mesh of the panels. In order to apply the "Gunite", there must be backing material adjacent to the wire mesh to be embedded in the 10 "Gunite". In encasing the piles their surfaces supply the necessary backing but a suitable backing must be constructed at the panels. In the event that the wharves or piers are already provided with wooden stops at points where it is 15 desired to place "Gunite" stops, the wooden stops may be used for backing purposes.

In forming the panels and the coverings of the piles, a mixture of cement and sand in proper proportions is blown from a shooting device, such 20 as a "Cement Gun", through a nozzle where water is supplied in sufficient quantity and in such a manner as to hydrate thoroughly the cementitious mixture without providing an excessive amount of water. From the nozzle, the material is blown 25 at a high velocity against the backing where it collects and builds up so as to enclose the reinforcing mesh. In substance the material is pneumatically tamped to form a dense cohesive mass constituting the material above referred to 30 as "Gunite".

Other features, objects and advantages will appear upon consideration of the following description and of the drawings, in which

Fig. 1 is a horizontal section of a wharf embodying a preferred form of the fire stop of the present invention, the section being taken through the supporting piles and the outer edge of the wharf being indicated by a dot-and-dash line;

Fig. 2 is a similar section of a pier;

Fig. 3 is a section taken along the line 3—3 of Figs. 1 and 2; and

Fig. 4 is a horizontal section through the pile at one end of a fire stop.

Referring to Fig. 1 of the drawings, reference 45 numeral 10 indicates a wharf arranged marginally with respect to the shore or bank 11 and including wooden supporting piles 12 and a deck 13. The piles may be arranged in rows extending from the shore to the outer edge of 50 the wharf and as indicated in Fig. 3 support heavy cap pieces or beams 14 which may extend outwardly from the shore along the rows of piles already referred to. Mounted on the cap pieces 14 are a string piece 15 at the outer edge of 55

the wharf and stringers or joists 16 arranged at regular intervals between the string piece 15 and the shore. The deck or floor 13 may be formed of planks resting on the string piece and joists.

- 5 As indicated in Fig. 1, the wharf is provided with a fire stop 18 comprising a main portion extending along a row of piles 12 from the shore to the outer edge of the wharf and guarding means, which may be in the form of wings 19, 10 to prevent fire beneath the deck from jumping around the ends of the fire stops. The fire stop proper and also the wings 19 should extend right up to the floor as indicated in Fig. 3. The wings 19 may extend to any suitable distance along 15 the edge of the wharf but will give satisfactory results if they extend merely from the pile, at the outer end of the row with which the main body of the fire stop is connected, to the piles at the outer ends of the next adjacent rows. 20 It is also important to have the fire stop strongly fire resistant and to protect the fire-stop-supporting piles substantially to the extent of fireproofing the same. Preferably these results are obtained by stretching reinforcing 25 material, such as wire mesh 20 along the piles where the fire stop is to be located, placing wire mesh around the stop-supporting piles, providing backing forms for the panels between the piles and blowing hydrated cementitious material 30 into place so that the wire mesh will be completely embedded in "Gunite" and the piles will be completely encased in a thick casing of such material. Obviously if a wooden fire stop be already in position, all or parts of the same may be 35 used as a backing for the panels of reinforced "Gunite".

When fire stops are to be constructed for a pier such as shown in Fig. 2, both ends of the fire stops must be provided with wings 19 since both 40 sides of the pier are exposed. Otherwise the construction may be exactly the same as for the wharf shown in Fig. 1.

The reinforced "Gunite" panels are very strong and flexible and not easily damaged and the supporting piles are rendered substantially fire-proof. Obviously stops of the structure described 45 will cut off drafts very effectively and will actually check fires as well.

50 Preferably the "Gunite" covered piles are protected by fender piles 21.

It should be understood that various changes 55 may be made in the construction and arrangement of parts and the various features may be used without others without departing from the true scope and spirit of the invention.

Having thus described my invention, I claim:

1. The combination with an elongated structure of the type described comprising a deck, piles arranged in rows extending transversely with respect to the length of the deck, cap pieces on the piles of said rows, a string piece and stringers 5 on said cap pieces and supporting said deck, of a fire stop including openwork metal reinforcing sheet material supported by the piles of one of said rows and by said stringers to extend up to said deck between said stringers and additional 10 reinforcing sheet material at the inner sides of the outer piles of the fire stop row and the two adjacent rows and at the inner side of the string piece, reinforcing sheet material around all of the supporting piles, and dense fire resisting 15 cementitious material encasing said reinforcing material to form reinforced panels between the piles, encasing said piles to render them substantially fire-proof, and covering the inner side of the string piece to protect the same. 20

2. The combination with a wharf including a deck and supporting piles in rows extending from the shore to the outer edge of the wharf, of a monolithic fire stop of reinforced "Gunite" and comprising relatively thin panels between the 25 piles of one row, casings around the piles and a wing extending from the outer pile of the row along the edge of the wharf.

3. The combination with a wharf including a deck and supporting piles in rows extending outwardly from the shore, of a monolithic fire stop of reinforced "Gunite" comprising relatively thin panels between the piles of a row, casings around the piles of the row and wings extending from the outermost pile in the row in opposite directions 35 along the edge of the wharf.

4. The combination with an elongated structure of the type described comprising a deck, piles arranged in rows extending transversely with respect to the length of the deck, cap pieces on the 40 piles of said rows and stringers on said cap pieces supporting said deck, of a fire stop including openwork metal reinforcing sheet material attached to the piles of one of said rows and extending up to said deck and additional reinforcing sheet material connecting the outer piles of the fire stop row and an adjacent row, reinforcing sheet material of the same general character around all of the piles used to support the fire stop; and dense cementitious fire resisting material 45 encasing said reinforcing material to form reinforced panels between such supporting piles and encasing such piles to render them substantially fire-proof. 50
